W. B. THOMPSON

MAGNETIC T-SQUARE

Filed Feb. 12, 1927

FIG. 2.

FIG. 3.

Wade B. Thompson, INVENTOR

BY Victor J. Evans

ATTORNEY

WITNESS:

UNITED STATES PATENT OFFICE.

WADE B. THOMPSON, OF DETROIT, MICHIGAN.

MAGNETIC T-SQUARE.

Application filed February 12, 1927. Serial No. 167,789.

This invention relates to geometrical instruments and particularly to an improvement on the structure of the T-square as disclosed in my Patent No. 1,245,821 patented 5 on November 6th 1917.

The primary object of the present invention is to provide a simplified structure of a T-square which includes magnetic means adapted to attract and hold the T-square to 10 surfaces of certain characteristics, so that the hands of the user of the T-square will be free to use other instruments or for any other desired purpose.

This invention also consists in certain 15 other features of construction and in the combination and arrangement of the several parts, to be hereinafter fully described, illustrated in the accompanying drawings and specifically pointed out in the appended 20 claims.

In describing my invention in detail, reference will be had to the accompanying drawings wherein like characters denote 25 like or corresponding parts throughout the several views, and in which:

Figure 1 is a fragmentary top plan view 30 of a T-square which forms the subject matter of the present invention with parts broken away to clearly illustrate the construction.

Figure 2 is a perspective view of the T-square with the blade broken away.

Figure 3 is a vertical sectional view taken 35 through a drawing board and the head of my improved T-square and showing the application of the latter with the board.

Referring to the drawings in detail the reference numeral 1 indicates the blade which is of the usual construction, and is 40 fixed to the head 2 through the medium of a plurality of screws 3 as best shown in Figures 1 and 2 of the drawings. The head 2 is provided with recesses 4 disposed upon opposite sides of the point of connection of 45 the blade 1 therewith to receive horse shoe magnets 6 which have their poles formed with annular grooves 7 having inwardly inclined side walls so as to be fixed in openings 8 formed in a metallic strip 9 fixed to 50 the inner surface of the head through the

medium of screws 10 as best shown in Figure 1 of the drawings.

While I have disclosed a drawing board 12 having secured to its edges a strip 13 of magnetic material for cooperative association with the magnets, I wish it to be clearly understood that the T-square as shown may be used directly on iron structures that are 55 being erected.

From the above description and disclosure 60 in the drawings, it will be obvious that my improved T-square is extremely simple, yet functions adequately and effectively to hold itself to a drawing board provided with the magnetic strip 13, or to iron or steel beams 65 or other pieces of iron structure so that the hands of the user of the T-square may be free to use other instruments or for any other desired purpose as above set forth.

It is thought from the foregoing description 70 that the advantages and novel features of my invention will be readily apparent.

I desire it to be understood that I may 75 make changes in the construction and in the combination and arrangement of the several parts, provided that such changes fall within the scope of the appended claims.

What I claim is:

1. A T-square of the character described 80 comprising a blade, a head fixedly secured thereto and being provided with recesses along its contact face, horse shoe magnets in the respective recesses and a metallic strip secured to the said face and receiving 85 the poles of the horse shoe magnet for the purpose specified.

2. A T-square of the character described 90 comprising a blade, a head therefor, horse shoe magnets arranged in said head, means secured to the contact face of said head and receiving the poles of said magnets, and said poles passing through said means and adapted for attracting and holding the magnet to 95 surfaces of certain characteristics.

3. A head for a T-square, said head being provided with recesses arranged along its contact face, horse shoe magnets disposed in the respective recesses, a metallic strip secured to said face and being provided with 100

openings, and said magnets having their poles provided with annular grooves formed with inclined surfaces to be secured in said openings.

5. 4. A T-square of the character described comprising a blade, a head secured to said blade and being provided with recesses along its contact face, a strip having spaced pairs

of openings arranged therein and being secured to said face, magnets arranged in said recesses and passing through the respective openings for association with magnetic material whereby the T-square will be held in fixed relation to said material.

In testimony whereof I affix my signature.
WADE B. THOMPSON.
